PHOTOELECTRIC TRANSMITTER
SYNCHRONIZER

Louis M. Potts, Evanston, Ill., assignor to Teletype Corporation, Chicago, Ill., a corporation of Delaware

Application June 15, 1944, Serial No. 540,456

18 Claims. (Cl. 178—17)

The present invention pertains to printing telegraph apparatus and more particularly to improvements for photoelectric transmitters.

In the operation of photoelectric transmitters for telegraph systems it is necessary that the tape bearing the messages in code form be fed at a speed which corresponds to and is in phase with the speed of rotation of the scanning cylinders. This is customarily done by means of feed perforations or their equivalents in the tape. However, when only printed marks or their equivalents are provided in place of the perforations a different condition exists. In the event that proper phasing does not exist between the tape feed and the scanning mechanisms, perfect signaling will not result during transmission.

Accordingly, it is the object of this invention to provide means for phasing the tape feed and scanning operations.

A further object is to provide means automatically responsive to tape feed control signals printed on the tape for causing the operation of the phasing means.

The foregoing and other objects of the invention are achieved by providing a photoelectric cell which is responsive to an out-of-phase condition between an opening in a scanning cylinder and printed tape feed control marks on a tape which, in turn, through an amplifier, and oscillator, control the operation of a magnet. The operation of the magnet, responsive to an out-of-phase condition, results in its armature producing a drive disconnecting and a braking effect on the means which drive the tape feed means. Thus, every time that the printed feed marks on the tape are not in complete phase with the feed openings in the rotating scanning cylinder the speed of the tape feed means will be altered thereby resulting in the tape being fed at a slower rate momentarily until such time as the tape feed and scanning operations are once again in phase.

A better understanding of the invention may be had from the following description taken in conjunction with the accompanying drawings wherein like reference characters designate similar parts throughout the several views, and in which:

Fig. 1 is a vertical cross section view, partly broken away, taken through the optical axis and the scanning mechanism of the apparatus embodying the invention;

Fig. 2 is a plan view of the apparatus dis- 55

closed in Fig. 1 with the optical system and a part of the cover broken away;

Fig. 3 is a sectional view taken approximately on line 3—3 of Fig. 1;

Fig. 4 is a sectional view taken approximately on line 4—4 of Fig. 2;

Fig. 5 is an exploded view in perspective of the scanning mechanism of the device shown in Fig. 1;

10 Fig. 6 is a schematic diagram of an electrical circuit both for message transmission and for the phasing means embodying the present invention; and

15 Figs. 7 to 10, inclusive, show the type of tape utilized in the present apparatus and the means whereby such a tape may be prepared.

Having reference to Fig. 1, it is to be noted that the photoelectric transmitter embodying the present invention is of the type substantially disclosed and described in U. S. Patent No. 2,177,077, issued on October 24, 1939, to L. M. Potts. However, the apparatus to be described hereinafter differs in certain essentials from the above-mentioned patent and accordingly, the following description will include a description of the photoelectric transmitter to an extent necessary for an understanding of the present invention.

The apparatus as disclosed in Fig. 1 comprises an optical system indicated generally by the numeral 11, scanning mechanism indicated generally by the numeral 12, and the mechanism for operating the scanning mechanism, driving the tape feed mechanism, and phasing the two latter mechanisms, indicated generally by the numeral 13.

The optical system 11 comprises a housing 14 mounted by means of legs 16 to the top plate 17 of the apparatus. A cap 18 is provided which is securely fastened within the rightward end of the housing 14, as viewed in Fig. 1, and which carries an electrical socket 19 securely fastened therein. An incandescent bulb 21 is provided within the socket 19. Positioned in front of the light bulb 21 in a frame 22 in a lens 23 which directs the light rays from the incandescent bulb 21 onto a mirror 24 which is positioned in the housing 14 at a 45° angle so as to reflect the light rays from a horizontal plane to a vertical plane through a cylindrical lens 26 carried in a frame 27 which is also secured in the housing 14. The mirror 24 is held in place by means of a cover plate 28. A cover 29 is provided which is made of glass or some other transparent material and which is secured over

an opening cut in the top frame 17 immediately under and aligned with the cylindrical lens 26. The light rays reflected from the mirror 28 will thus be able to pass through the cover 29.

A tape indicated generally by the numeral 31 and clearly seen in Figs. 2 and 9 is designed to be used with the present apparatus. Inasmuch as no similar tape is known in the art, means have been shown, namely, Figs. 7, 8, and 10, by which such a tape may be printed. Referring to Fig. 9, the tape is shown as having a series of printed marks thereon. As seen in this view the lower marks 32 are spaced somewhat apart from the group of upper marks and are arranged so that one of the marks 32 corresponds to each transverse row of marks on the tape. These marks 32, which are slightly narrower in width than the other marks 33, are utilized as tape feed control marks for a purpose to be described herein-after. The upper marks 33 are arranged in transverse rows with a maximum of five marks to the width of a row. These rows are, as mentioned, aligned transversely on the tape 31 and also are aligned lengthwise of the tape. The width transverse of the tape provides for five of the marks 33 which correspond to the five impulses in a standard code, such as the Baudot, used in telegraphic communication. It is to be noted that the marks 33 are of such size that if two marks are printed adjacent to each other either transverse of, or lengthwise with the tape they will be in abutment with each other. As mentioned above, no similar tape such as 31 is known, at present, in the art. It is to be noted, however, that a tape substantially similar to the extent that it discloses five printed code impulse marks is disclosed, with the printing thereof described, in U. S. Patent No. 2,284,679, issued on June 2, 1942, to L. M. Potts. Thus, it may be seen that the difference between the tape utilized in the present invention and that known to the prior art is in the addition of marks to control the feed of the tape, rather than the usual sprocket feed by perforations running lengthwise of the tape.

Figs. 7, 8, and 10 disclose modifications which may be made to the patent mentioned immediately above for the purpose of producing a tape such as tape 31. Fig. 7 of the present drawing is a modified view of Fig. 10 of the above-mentioned Potts patent wherein every time that the rotating cam 34 presents one of its apices 36 to the cam follower 37 the follower will be rotated in a clockwise direction as viewed in Fig. 7 and its opposite end (not shown) will come in contact with a holding magnet which is not shown. In the event that the magnet has been energized by incoming signals the armature will be retained in an attracted position, thus acting to unlock certain other mechanism and allow a printing operation to occur, if other conditions exist at this time. The operation of cam follower 37 and cam 34 has been completely described in the patent mentioned above relative to printing of tape similar to tape 31, the only difference being that the cam 34 has an apex section 38 of long dwell. This latter apex section provides a condition whereby the tape feed mark 32 may be invariably printed on the tape assuming other conditions to exist at the time. Referring now to Fig. 8, which is a modification of Fig. 15 of the above-mentioned patent, it may be seen that the essential difference herein is in the inclusion of a print lug 39 which is smaller in size than the sixth print lug shown in the above-mentioned patent.

Print lug 39 is for the purpose of printing the tape feed control marks 32 on the tape 31, whereas the sixth print lug disclosed in Fig. 15 of the above-mentioned patent was similar to the remaining five lugs and was used for printing a sixth mark similar to the other five inasmuch as that patent discloses a sixth unit rather than a five unit communication code. Likewise, the outer periphery of the cam 41 to which the print lugs are secured has been altered somewhat in the shape of its cut. This has been necessary in order to provide for the printing of the five code marks for the five unit communication code and also for the tape feed marks 32 by means of the print lug 39. Fig. 10 discloses a development of the print lugs shown in Fig. 8, clearly disclosing the position of the special print lug 39 for the tape feed control marks with respect to the print lugs for the five unit communication code. Inasmuch as a complete operation of the printing of the tape has been clearly described in the above-mentioned patent, it is not deemed necessary to go through the printing operation again in this specification. Accordingly, the reader is referred back to this patent to be read in light of the modified apparatus, as disclosed in Figs. 7, 8, and 10, whereby it is believed a complete understanding of the tape printing for tape 31 may be obtained.

Referring now to Fig. 5, there is disclosed therein the scanning cylinders which comprise a part of the scanning apparatus indicated generally by the numeral 12. As may be seen in this view, the cylinders are three in number and their contemplated use in the apparatus is one within the other. The cylinder 42, which is shown at the extreme left of Fig. 5, is the innermost cylinder in the group and is stationary with respect to the apparatus and the other two cylinders. The cylinder 42 has a built-up section 43 extending over a part of its periphery. The built-up section 43 has a plurality of openings therein of which numeral 44 corresponds to a start pulse, numerals 46, which are five in number, correspond to the five code impulses for the five unit message communication code, and numeral 47 corresponds to the tape feed control marks on the tape. The intermediate cylinder 48 is formed with a plurality of six openings 49 extending spirally around the outer surface of the cylinder 48 and which correspond to the openings 44 and 46 in the cylinder 42. A shaft 51 is provided for the cylinder 48, the cylinder being rotated thereby in a manner later to be described. The third or outer cylinder 52 is rotated independently of the cylinder 48 by means of a sleeve 53 which is securely fastened to the cylinder 52 and which surrounds the shaft 51 of the cylinder 48 when the cylinders are assembled. The cylinder 52 is formed with a plurality of small rectangular openings 54 extending completely around the periphery thereof which are so positioned that when the cylinders are assembled the openings 54 will coincide with the opening 44 in the cylinder 42 and the extreme rightward opening 49 in the cylinder 48. The purpose of these openings is to scan the start pulses to be transmitted over the line conductor. A plurality of long rectangular openings 56 are also provided in the periphery of the cylinder 52, these openings likewise extending completely around the outer periphery of the cylinder a small distance apart. When the cylinders are assembled the openings 56 are of such length as to coincide with the five remaining openings 49.

in the cylinder 48 and the five openings 46 in the cylinder 42. These openings are provided to scan the five impulses utilized in the standard five unit permutation code. A third group of openings 57 are also provided in the periphery of the cylinder 52, likewise extending completely around the cylinder. These openings 57 coincide with the opening 47 in the cylinder 42 when the three cylinders are assembled and are used to scan the tape feed control marks. It is to be noted that no aligned openings are necessary in the intermediate cylinder 48, as the left end of this cylinder does not extend as far as the openings 47 and 57, as may be seen in Fig. 1. The two cylinders 48 and 52 are rotated independently of each other, both with respect to the stationary cylinder 42, at such a speed that the outer cylinder 52 will move a distance equal to the distance between two adjacent rectangular openings 58 while the intermediate cylinder 48 is rotating a distance equal to a complete revolution. The rotation of the two cylinders and the resulting scanning operation has been clearly described in the above-mentioned patent relating to the photoelectric transmitter.

Referring now to Fig. 1, it is to be noted that the cylinders, described immediately above, when assembled are in such a position that their openings will underlie the transparent plate 29 in direct alignment with the reflected light rays from the mirror 24. Positioned within the inner cylinder 42 and extending outwardly therefrom through a light tight cover 58 are a plurality of light conducting rods which may be of any suitable material, such as methyl methacrylate resin, for example. One of these rods 59 is positioned immediately below the openings 54 in the cylinder 52, and is extended through the opening 44 in the cylinder 42 to a height so that it is flush with the outer surface of the built-up section 43. The rod 59 is utilized to conduct any light which, as a result of the scanning operation, may indicate that a start pulse is to be transmitted. To the left of the light conducting rod 59, as viewed in Fig. 1, are a plurality of five similar light conducting rods 61 which extend through the openings 46 in the cylinder 42 to the built-up surface. These five rods 61 are provided to conduct any light which may result during the scanning operation indicating the five impulses of the five unit code. At the extreme left is a similar light conducting rod 62 which extends upwardly through the opening 47 in the cylinder 42 and which is aligned with the openings 57 in the cylinder 52. The light conducting rod 62 is provided to indicate the presence of light during the scanning operation and is for the purpose of controlling the phasing mechanism under the control of the tape feed control marks. The light conducting rod 59 and the rods 61, after they leave the cylinder 42 through the cap 58, are disposed in such a manner that their opposite ends will be adjacent to a photoelectric cell 63. Likewise, the light conducting rod 62 is also disposed in such a manner that its opposite end will be adjacent to a photoelectric cell 64. It is to be noted that in the use of light conducting rods, such as those utilized and described above, the light rays passing into one end will be conducted through and follow the contour of the light conducting rod until they pass out the opposite end even though the rod may be bent in any desired direction. Thus, if any light rays pass into the upper ends of the light conducting rods during the scanning opera-

tion they will be conducted completely through the rod, following its contour, until they pass out the opposite end, thus causing activation of the adjacent photoelectric cells 63 and/or 64. The activation of these cells and the resulting operations therefrom will be described completely hereinafter. The use of such type rods permits the placing of the photoelectric cells at any convenient location.

- 10 It might be mentioned at this point that the tape 31 passes under the transparent cover 29 and immediately above the outer cylinder 52. This may be observed clearly by referring to Fig. 3, wherein it is to be noted that the tape 31 actually engages the outer periphery of the cylinder 52 for a short distance. The tape 31 is fed toward the left, as viewed in Fig. 3, by means of a friction roll 66 which is positioned on a shaft 67 and caused to rotate by means which will be described hereinafter. The friction drive roll 66 underlies the tape 31 which is caused to be positively forced into engagement with the outer periphery of the friction roll 66 by means of a pressure roll 68 which is immediately above the tape 25 31 and aligned with the roll 66. The pressure roll 68 is positioned on a shaft 69 which in turn is rotatably positioned at the end of a lever 71 pivotally mounted on a shaft 72. The opposite end of the lever 71 has a spring 73 secured thereto, the opposite end of which may be secured to any convenient member in the frame of the machine. The spring 73 normally urges the lever in a clockwise direction, as viewed in Fig. 3, thereby causing the roll 68 to engage the tape 31 and force it against the outer periphery of the friction drive roll 66.

By referring to Fig. 3 it will be seen that the cylinders are held securely in position by means of a semi-circular bracket 74 which is securely fastened at its lower extremity to the frame of the apparatus. By referring to Fig. 1 it may be seen that the bracket 74 does not actually encompass the cylinder 52 but instead acts as a support for the sleeve 53, connected to the cylinder 45 52, at a position immediately adjacent the end of the cylinder.

The shaft 51, as may be seen in Fig. 1, extends the entire length of the apparatus and is supported at its extremity opposite from the cylinder 50 48 by means of a bearing bracket 76. Adjacent the bearing bracket 76 is a motor 77 which through motor shaft 78 drives a pinion gear 79 keyed to the end of the motor shaft. A gear 81, secured to a short sleeve 82, is provided to engage 55 the pinion gear 79 and is mounted rotatively therewith on the shaft 51. The sleeve 82 terminates in a driving face 83 of a standard clutch unit. Opposed to the driving face 83 is a driven face 84 which is secured to the shaft 51 but which 60 may move laterally through the urging of a spring 86. The driven face 84 is under the control of a magnet armature 87, as is the usual practice, and in operation when the armature is moved by the energization of a magnet 88, the spring 86 will 65 urge the driven face 84 into engagement with the driving face 83 and thereby causes rotation to be imparted to the shaft 51 from the gear 81. Thus, it may be seen that the energization or de-energization of the magnet 88 controls the operation 70 of the photoelectric transmitter, and its energization may be under the control of a manual switch or a taut-tape device, well known in the art, associated with any keyboard device which might be utilized to prepare the tape used in 75 transmission.

A gear 89 is securely fastened to the shaft 51 to rotate therewith, and in turn imparts motion to a gear 91 which is mounted on a stub shaft 92 which is positioned in the framework of the apparatus. The gear 91, in turn, has a gear 93 secured thereto to rotate therewith and which drives a gear 94 rotatively mounted on the shaft 51, to rotate independently of the shaft. The gear 94 has a companion gear 96 connected thereto, also rotatively mounted with respect to the shaft 51, which drives a gear 97 rotatively mounted on the stub shaft 92. The gear 97 has a gear 98 secured thereto, for rotation therewith, which drives a gear 99 which is securely fastened to the sleeve 53 extending from the cylinder 52. The sleeve 53, which is mounted about the shaft 51, is free to rotate independently of the shaft 51 with respect thereto on a pair of ball bearings 100 located between the sleeve and the shaft. It may be seen that the gear train which has just been described is necessary in order that the speed of rotation of the cylinder 52 may be decreased to the amount necessary so that the cylinder moves only a distance equal to the distance between adjacent openings 56 therein during the time that the intermediate cylinder 48 is rotating one entire revolution. Thus, the entire gear train just described acts as a gear reduction unit.

Referring to Fig. 2 it is to be seen that a stub shaft 102 is positioned parallel to the shaft 51 and mounted in the frame adjacent thereto. The stub shaft 102 has a gear 103 securely fastened thereto which is so positioned on the shaft 102 that it is engaged by the gear 99 on the sleeve 53 and driven thereby thus imparting rotation to the shaft 102. The shaft 102 has a plate 104 securely fastened toward its opposite end which has a disc 105 of friction material attached thereto. Thus, upon any rotation of the shaft 102, the plate 104 and the friction disc 105 will rotate therewith. A member 107 is rotatively positioned on the shaft 102, having at its right side, as viewed in Fig. 2, a plate 108 adjacent to the friction disc 105. The member 107 is formed at its left side with a plate 109 similar to plate 108, the plate 109 terminating in a leftwardly extending sleeve 110 mounted about the shaft 102. The member 107, which it was mentioned is rotatively mounted on the shaft 102, may also be given a slight lateral movement with respect to the shaft by means of a pair of arms 112 which straddle the small diameter section of the member 107 located between the two plates 108 and 109. Securely fastened to the sleeve 110 is a gear 113 which rotates with the sleeve 110 at such times that motion is imparted thereto. A friction disc 114 is secured to the frame of the machine adjacent to and immediately to the left of the plate 109 of the member 107, as viewed in Fig. 2.

It is to be seen that the shaft 67, previously mentioned as driving the friction drive roll 66, terminates in a bearing bracket adjacent to the shaft 102. The shaft 67 has a gear 116 securely fastened toward its extremity opposite from the friction roll 66, which is located adjacent to and driven by the gear 113 secured to the sleeve 110. Thus, rotary motion may be imparted to the gear 116 and thus to the shaft 67 and the friction drive roll 66 by the gear 113 at such time as the latter gear and the shaft 110 are rotating.

By referring to Figs. 1 and 4, it may be seen that the pair of arms 112 which straddle the member 107 and impart lateral movement thereto under certain conditions are pivotally mounted on a shaft 117 with their lower extremities 118

forming the armature of a magnet 119. A spring 120 is provided which is connected to the lower extremity 118 and normally urges the armature in a clockwise direction, as viewed in Fig. 1, resulting in the arms 112 urging the member 107 toward its rightward position, as viewed in Fig. 1, with its plate 108 in engagement with the adjacent friction disc 105. This latter condition exists at such times that the magnet 119 is in its de-energized condition.

During the operation of the apparatus, the magnet 88 will be energized, thus causing the armature 87 to be removed from engagement with the clutch mechanism thereby allowing the spring 86 to urge the driven clutch face 84 into engagement with the driving clutch face 83, thereby causing rotation of the shaft 51. The shaft 51 directly drives the intermediate scanning cylinder 48 and through the gear 89 secured to the shaft and the gear reduction mechanism causes rotation to be imparted to the sleeve 53 and thus to the cylinder 52. In this manner, rotation is imparted to both of the scanning cylinders 48 and 52, and the scanning operation occurs in a manner similar to that described in the above-mentioned patent disclosing the photoelectric transmitter. During this normal operation, the magnet 119 is de-energized and the spring 120, through the arms 112, causes the member 107 to be moved as viewed in Fig. 1 with its plate 108 in engagement with the friction disc 105. At this time, inasmuch as the shaft 102 is being driven by the gear 99 engaging the gear 103, the plate 104 secured to the shaft 102 will cause rotation to be imparted to the member 107 and thus to the sleeve 110 secured thereto. Rotation of the sleeve 110 causes gear 113 to be rotated, which in turn through its driving relationship with gear 116 secured to the shaft 67, causes the shaft 67 to be rotated which through the friction drive roll 66 mounted at its opposite extremity causes the tape 31 to be fed through the scanning apparatus. It might be mentioned at this point that the tape 31 is fed at a speed somewhat greater than the speed of rotation of the cylinders in order to assure that the code marks on the tape will coincide with the scanning openings in the cylinders through the operation of the phasing means. During this operation of the apparatus, the tape feed control marks 32 on the tape 31 will coincide with the openings 57 in the cylinder 52 and the opening 47 in the cylinder 42. Inasmuch as the tape feed marks 32 are printed they will block any light rays from passing from the mirror 24 through the scanning openings 57 and 47 to the light conducting rod 62. Accordingly, the photoelectric cell 64 will not be activated at this time. Thus, the scanning operation occurs with both the tape 31 and the cylinders 48 and 52 continuously moving.

In the event that the tape feed becomes out of phase with the rotation of the cylinders 48 and 52, the tape feed control marks 32 on the tape 31 will not be completely aligned with the openings 57 in the cylinder 52 and the opening 47 in the cylinder 42, as previously described, to block any light rays from passing to the light conducting rod 62. When this condition exists, a certain amount of light from the incandescent bulb 21 will be passed through the openings 57 and 47 and to the light conducting rod 62. The light rays so passed through will follow the contour of the light conducting rod 62, as previously described, to the opposite extremity adjacent to the photoelectric cell 64. Referring now to Fig. 6,

the impingement of light upon the light sensitive cathode 122 of the photoelectric cell 64 causes the emission of electrons therefrom which flow toward the anode 123 of the photo cell. The photoelectric cell 64 is supplied with operating voltage from a source 124, and ordinarily, changes in the electron stream flowing within the cell, due to varying light intensities falling upon the cathode 122, will cause varying potential differences to be set up across a resistance 125 which is connected in series with the anode 123 of the photo cell. The electrical circuit for the unit just described may be considered as extending from the positive side of the voltage source 124, over a conductor 127, through a resistance 128, through a tap 129, through the resistance 125, through the photoelectric cell 64, through the conductor 130, and back to negative potential at the voltage source 124.

The resistance 125 is also connected in the grid circuit of a vacuum tube amplifier 132 over a conductor 133. The activation of the photo cell 64 causes a voltage drop across the resistance 125 which results in a grid 134 of the vacuum tube 132 becoming less negative. The result of the grid 134 becoming less negative (or positive) results in the vacuum tube 132 becoming conductive, in a manner well known in the art. The circuit of the amplifier stage just described may be considered as from the positive side of the voltage source 124, over the conductor 127, through the resistance 128, through a tap 135, through a resistance 136 in series with the anode of the vacuum tube 132, through the vacuum tube, over a conductor 137, through the resistance 128, and to the negative side of the voltage source 124. The operation of the vacuum tube 132 results in a voltage drop across the resistance 136 in a manner which is well known in the operation of such tubes.

The resistance 136 is also connected in series in the grid circuit of a gas filled oscillator tube 139. The result of the voltage drop previously described across the resistance 136 results in a grid 140 of the gas filled tube 139 becoming less negative which causes the tube 139 to operate, in a manner well known in the operation of gas tubes. In tracing the circuit for the gas tube 139 upon its operation it is necessary to note that the magnet 119 is serially connected in the plate circuit of tube 139. Thus, the plate circuit of tube 139 may be traced from the positive side of the voltage source 124, through the conductor 127, through a resistance 141, over a conductor 142, through the winding of the magnet 119, over a conductor 143, through the gas filled tube 139, over a conductor 144, through the resistance 128, to the negative side of the voltage source 124. It is to be noted that a condenser 146 is placed in shunt relationship to the gas filled tube 139, between the conductor 143 and the resistance 128. Assuming that the condenser 146 is in a charged condition, upon such time as the grid 140 of the gas tube 139 becomes less negative, the condenser 146 will discharge over the circuit just described; that is, through conductor 147 and the tube 139.

It is to be noted, however, that the frequency of charge and discharge of the condenser 146 is so high that none of this frequency of current will pass through the windings of the magnet 119, but only direct current will pass therethrough. This high frequency current exists only through a circuit including the condenser 146, the conductor 147, and the plate circuit of the tube 139.

In the usual gas filled tube it is to be noted

that once the tube starts conducting, it will continue to be conductive independently of the grid control until such time as the circuit is broken. However, in the present operation, at the time 5 that the condenser 146 discharges, the plate voltage will drop and the grid 140 will resume control of the tube 139. Due to the fact that there is a certain amount of potential continuously flowing in the circuit described above, the condenser 146 will once again discharge, causing current to flow through the conductor 147 and through the tube 139. This will occur very rapidly and in succession to an amount necessary to build up sufficient potential to cause the magnet 119 to become energized. The result of the energization 10 of the magnet 119 will be described immediately hereinafter, but it is believed necessary at this time to point out how the tube 139 will stop discharging. Therefore, assuming that the tape and scanning means are once again in phase, 15 resulting in the photoelectric cell 64 not being activated to cause an emission of electrons therefrom, the grid 134 of the vacuum tube 132 will resume its normal negative potential thus causing no great voltage drop across the resistance 136. With no great voltage drop across the resistance 136, the grid 140 of the gas tube 139 will once again become negative. After the condenser 146 had discharged during the previous operation 20 and caused current to pass through the conductor 147 and the tube 139, the plate voltage of the tube had dropped to an amount whereby the grid 140 had resumed control of the tube. The grid 140 keeps control of the tube 139 until such time as a sufficient amount of potential is charged up in 25 the condenser 146 for it to again discharge. If during the time that the condenser 146 is charging, the grid 140 becomes negative again, then at the time that a potential is reached in the condenser 146 sufficient for its discharge this will 30 not occur because the grid 140 has become negative and the gas tube 139 will not operate. Therefore, it may be seen that the tube 139 will resume its normal condition and will not again operate to allow current to be passed therethrough until 35 such time as light rays once again impinge on the cathode 122 of the photoelectric cell 64 causing the photoelectric cell 64 and the vacuum tube 132 to be placed in their operating conditions. After the tube 139 is no longer operating, the magnet 119 will become de-energized because 40 there will not be a sufficient current passing through its winding to cause it to stay magnetized. Referring now to Fig. 1, the energization of the magnet 119 causes its armature 118 to be attracted 45 thereto, pivoting about the shaft 117. This results in the arms 112 being moved from their rightward position (Fig. 1) toward the left against the tension of the spring 120. By referring to Fig. 2, it may be seen that upon the arms 50 112 being moved toward the left, the member 107 will be moved therewith, which results in the plate 108 no longer being in driven engagement with the friction disc 105 of the rotating plate 104. Upon such happening, rotation will no 55 longer be imparted from the gear 103, the shaft 102, the plate 104, and through the member 107 to the sleeve 110 and the gear 113. With gear 113 no longer being rotated, any change in speed 60 of rotation of this gear will result in a similar change or reduction in the speed of rotation of

the gear 118 in engagement therewith. Likewise, a change in speed of the rotation of gear 118 results in a similar change in speed of the shaft 67 and the friction drive roll 68. This, of course, will also be imparted to the tape 31 and thereby change the feeding speed of the tape. Further, when the member 107 moves toward the left, as viewed in Fig. 2, its associated plate 109 engages the friction plate 114 secured to the frame work of the machine. The effect of the plate 109 engaging the friction plate 114 is to cause a braking action to occur which tends to slow down the speed of rotation of the sleeve 110 and the gear 118 secured thereto. This causes a similar reduction in the speed of the gear 116, the shaft 67, and the friction drive roll 68. The member 107 will remain in its leftward position (Fig. 2) until such time as the change in speed of rotation of the shaft 67 and the friction drive roll 68 has been sufficient to cause a change of speed or movement in the tape 31 whereby the feed control marks 32 in the tape will once again be aligned with the openings 57 and 47 in the cylinders 52 and 42, respectively. At this time, the light will no longer be allowed to shine through the light conducting rod 62, the photoelectric cell 64 will no longer be activated, and the gas tube 139 will no longer operate, as described clearly above. The magnet 119 will thus de-energize.

By referring to Fig. 6 it may be seen that the photoelectric cell 63 which receives its light from the light conducting rods 59 and 61 has a vacuum amplifier tube 151 and a gas filled oscillator tube 152 associated in its circuit similarly to the circuit described above. The operation of these tubes will be similar to that previously described, upon the impression of light on the photoelectric cell 63 through any of the light conducting rods 59 or 61. However, instead of a magnet in this circuit there is a relay 153 which will be energized upon operation of the gas filled tube 152. The energization of the relay 153 causes an associated armature 154 to be attracted thereto, which completes an electrical circuit from a grounded battery 155, through a resistance 156, through the armature 154, and over a line conductor 157 to a receiving printer at a distant station designated schematically by the magnets 158. The transmission of code signals from such apparatus has been described by means of a substantially similar circuit in the above-mentioned patent relating to photoelectric transmitters.

It might be mentioned that it is not necessary for the operation of the above-mentioned apparatus that light conducting rods be used as disclosed herein. Instead it is possible to use a photoelectric cell directly within the inner scanning cylinder 42, as described in the above-mentioned patent relating to photoelectric transmitters. However, if such a photoelectric cell is utilized it will be necessary to have two separate cathodes therein, one of which is responsive to the light from the light conducting rods 59 and 61 for message code transmission and the second cathode is responsive to light from the light conducting rod 62 controlling the tape feed control marks and the scanning operation.

Although a specific embodiment of the invention has been shown and described, it will be understood that this embodiment is but illustrative and that various modifications may be made therein without departing from the scope and spirit of this invention.

What is claimed is:

1. In a photoelectric transmitter, in combina-

tion, a tape bearing printed code marks, means to feed said tape, means to scan said tape for message code marks and for tape feed control marks, means to generate telegraph signals on a single circuit according to the scanning of the message code marks, and means responsive to an out-of-phase condition between said tape feed means and said scanning means as indicated during the scanning of said tape feed control marks for causing said tape feed means to be brought into phase with said scanning means.

2. In a photoelectric transmitter, in combination, a tape bearing printed message code marks and tape feed control marks, means to feed said tape, means to successively scan said message code marks and to scan said tape feed control marks, means to generate telegraph signals according to the scanning of the message code marks, and means responsive to the scanning of said tape feed control marks to control said tape feed means.

3. In a photoelectric transmitter, in combination, a tape bearing printed message code marks and tape feed control marks, means to feed said tape, means to scan said message code marks and said tape feed control marks, means to successively generate telegraph signals according to the scanning of the message code marks, and means responsive to an out-of-phase condition between said tape feed control marks and said scanning means to control said tape feed means.

4. In a photoelectric transmitter, in combination, a tape bearing printed message code marks and tape feed control marks, means to feed said tape, means to successively scan said message code marks and to simultaneously scan said tape feed control marks, means to generate telegraph signals according to the scanning of the message code marks, and means including a photoelectric cell responsive to an out-of-phase condition between said tape feed control marks and said scanning means for causing said tape control marks and said scanning means to be brought into phase.

5. In a transmitter, in combination, a control form bearing permutation code indicia and phase control indicia, means to scan the permutation code indicia and the phase control indicia, means to transmit on a single circuit signals according to the permutation code indicia scanned, and means to control the phase of said scanning means and said control form by the scanning of the phase indicia.

6. In a transmitter, in combination, a control form bearing permutation code indicia and phase control indicia, means to scan said permutation code indicia and phase control indicia, means to produce a relative motion between said scanning means and said control form, means to successively transmit signals according to the permutation code indicia scanned, and means responsive to an out-of-phase condition between said phase control indicia and said scanning means for causing said phase control indicia and said scanning means to be brought into phase.

7. In a phase control device, a tape bearing phase control indicia, means to feed said tape, a gear train for driving said tape feed means, means to scan said tape, and means responsive to an out-of-phase condition between said phase control indicia and said scanning means for causing said tape feed means to be disconnected from said gear train.

8. In a phase control device, a tape bearing phase control indicia, means to feed said tape, a gear train for driving said tape feed means,

means to scan said tape, means responsive to an out-of-phase condition between said phase control indicia and said scanning means for causing said tape feed means to be disconnected from said gear train, and means for applying a breaking action to said tape feed means.

9. In a phase control device, a tape bearing phase control indicia, a source of illumination, means to scan said phase control indicia, means to feed said tape between said source of illumination and said scanning means, a gear train for driving said tape feed means, a photoelectric cell responsive to light rays from said source of illumination under the control of said scanning means, and means responsive to the activation of said photoelectric cell for causing said tape feed means to be disconnected from said gear train.

10. In a phase control device, a tape bearing phase control indicia, a source of illumination, means to scan said phase control indicia, means to feed said tape between said source of illumination and said scanning means, a gear train for driving said tape feed means, a photoelectric cell responsive to light rays from said source of illumination under the control of said scanning means, an amplifier tube under the control of said photoelectric cell, an oscillator tube under the control of said amplifier tube, and means under the control of said oscillator tube for disconnecting said tape feed means from said gear train.

11. In a phase control device, a tape bearing phase control indicia, a source of illumination, means to scan said phase control indicia, means to feed said tape between said source of illumination and said scanning means, a gear train for driving said tape feed means, a photoelectric cell responsive to light rays from said source of illumination under the control of said scanning means, an amplifier tube under the control of said photoelectric cell, an oscillator tube under the control of said amplifier tube, and means including a magnet under the control of said oscillator tube for disconnecting said tape feed means from said gear train.

12. In a phase control device, a tape bearing phase control indicia, a source of illumination, means to scan said phase control indicia, means to feed said tape between said source of illumination and said scanning means, a gear train for driving said tape feed means, a photoelectric cell activated by light rays from said source of illumination under the control of said scanning means, an amplifier tube operated by the activation of said photoelectric cell, an oscillator tube operated by the operation of said amplifier tube, and means responsive to the operation of said oscillator tube for disconnecting said tape feed means from said gear train.

13. In a photoelectric transmitter adapted to be controlled by a tape carrying groups of code impressions, each group corresponding to a character signal, a scanning device, means to operate the scanning device in similar cycles for each character signal transmitted, means for feeding the tape past said scanning device at a speed commensurate with said cycles, means for transmitting the character signals on a single circuit, and photoelectrically controlled means effective under the control of predetermined impressions in

said tape for supervising the operation of said tape feeding means.

14. In a photoelectric transmitter adapted to be controlled by a tape carrying groups of marks, each group comprising permutation code marks and tape feed marks, a scanning device, means to operate the scanning device in similar cycles for each group of marks, means for feeding the tape past said scanning device at a speed in phase with said cycles, means for successively transmitting the permutation code signals in each group, and photoelectrically controlled means responsive to an out-of-phase condition between said tape feed means and said scanning device as determined by said tape feed marks for causing said tape feed means to be brought into phase with said scanning device.

15. In a telegraph transmitter, a form bearing code impressions, form advancing means, transmitting means, a single means to drive said form advancing means and said transmitting means at fixed relative speeds, and means controlled by said code impressions to alter the advance of said form to maintain a fixed phase relation between the motion of said transmitting means and the motion of said form.

16. In a photoelectric transmitter, in combination, a tape bearing printed permutation code marks and tape feed control marks, means to feed said tape, means to scan said permutation code marks and said tape feed control marks, a photoelectric cell responsive to the scanning of said permutation code marks, a line conductor, means to transmit said permutation code marks over said line conductor, a photoelectric cell responsive to the scanning of said tape feed control marks, and means responsive to said last-mentioned photoelectric cell for controlling said tape feed means, whereby said tape will be fed in phase with said scanning means.

17. In a photoelectric telegraph transmitter, a tape bearing printed code marks and tape feed control marks, means to feed said tape, means to scan the code marks and the tape feed control marks, means to generate signals according to the scanning of the code marks, means including said scanning means and independent of the code marks and the tape feed control marks to generate a phasing impulse to accompany each signal group, and means controlled by the scanning of the tape feed control marks to phase the feed of the tape with the operation of the scanning means.

18. In a photoelectric telegraph transmitter, a tape bearing printed code marks and tape feed control marks, means to feed said tape, means to scan the code marks and the tape feed control marks, means to generate signals according to the scanning of the code marks, means including said scanning means and independent of the code marks and the tape feed control marks to generate a phasing impulse to accompany each signal group, a line conductor, means to transmit the generated signals and phasing impulse over said line conductor, and means controlled by the scanning of the tape feed control marks to phase the feed of the tape with the operation of the scanning means.

LOUIS M. POTTS.
